UNITED STATES PATENT OFFICE.

GOTTHILF ANSGARIUS BETULANDER, OF SÖDERTÖRNS VILLASTAD, SWEDEN, AND NILS GUNNAR PALMGREN, OF LONDON, ENGLAND, ASSIGNEES TO THE RELAY AUTOMATIC TELEPHONE COMPANY, LIMITED, OF LONDON, ENGLAND.

AUTOMATIC OR SEMI-AUTOMATIC TELEPHONE EXCHANGE SYSTEM.

1,251,955.

Specification of Letters Patent.

Patented Jan. 1, 1918.

Application filed July 6, 1915. Serial No. 38,173.

To all whom it may concern:

Be it known that we, GOTTHILF ANSGARIUS BETULANDER and NILS GUNNAR PALMGREN, subjects of the King of Sweden, 5 residing respectively, at Villa Castor, Söder-törns Villastad, Sweden, and Marconi House, Strand, London, England, have invented new and useful Improvements in Automatic or Semi-Automatic Telephone- 10 Exchange Systems, of which the following is a specification.

The invention relates to automatic or semi-automatic telephone exchange systems in which every group-selecting stage or section comprises a number of switching units each including a plurality of incoming and outgoing junction lines, common switching or selecting means associated with the incoming lines and separate connecting means 15 for effecting the connections between the incoming and outgoing lines. In systems of this kind a connection in a group-selecting stage is effected by first connecting the calling junction line with a group-selector accessible in common to all incoming junction lines of the same switching unit, this group-selector being then operated to select the wanted group of outgoing lines, whereupon the connection between the calling incoming 20 line and an idle outgoing line of the group selected is established through separate connecting means. As the group-selectors are used only for setting up the connections the number of such selectors may be very small. 25 For instance it may be sufficient to provide two group-selectors for every switching unit having ten incoming lines. The object of the present invention is further to reduce the necessary number of group-selectors by 30 better utilizing them and to reduce the probability of a call not getting through for want of selectors. According to the invention this is attained by making a larger number of switching units accessible to the subscriber's lines or the junction lines. For 35 that purpose the junction lines accessible in common to a group of subscriber's lines and leading to the first group-selecting stage are led into different switching units and, further, the junction lines extending in the 40 same direction from the various switching units of a group-selecting stage are led into different switching units of the next group-

selecting stage. For instance, every subscriber's line may have access to ten switching units of the first group-selecting stage and every junction line of a group-selecting stage may have access in every direction to ten switching units of the next selecting stage, whereas in the systems heretofore known a subscriber's line can only reach one switching unit and a junction line only one switching unit in each direction. With this arrangement it may be sufficient to provide only one group-selector for every switching 55 unit with say ten incoming lines. For the selection of a disengaged switching unit according to this invention, all non-engaged incoming lines of a switching unit are marked as engaged during the selecting 60 operation within the said unit. If required, however, two or more group-selectors may be allotted to every switching unit and in this instance a switching unit is not blocked 65 until all group-selectors of the same switching unit are simultaneously engaged.

In the accompanying drawings:

Figure 1 is a diagrammatic representation of a line arrangement for a 10,000-line system according to this invention;

Fig. 2 a modification;

Fig. 3 a practical application of the line arrangement of Fig. 2 with relays as connecting elements; and

Fig. 4 a modification of the system shown 85 in Fig. 3.

The same references are used for designating corresponding parts of the various figures.

In Fig. 1, L designates the subscribers' 90 lines which are grouped together in small groups G_1 , G_2 , G_3 and larger groups G_1 , G_2 , G_3 . In a 10,000-line system there are ten large groups G each comprising ten small groups g , each including a hundred subscribers' lines. Every group of one hundred subscribers' lines has access to a number of junction lines l_1 , l_2 , l_3 leading to the first group-selecting stage. In practice there may be ten such junction lines. It is to be 100 noticed that all lines are shown as single-wire lines although in practice they include two or more wires. The connecting possibilities are designated in Figs. 1 and 2 by small circles at the crossing points between 105 the lines which can be connected together,

the circles thus representing normally open contacts adapted to be closed by suitable connecting means such as selectors or relays. The switching and connecting means for establishing the connections between the subscribers' lines L and the junction lines l 5 constitute the preselecting stage S_1 .

The junction lines l accessible in common to a group g of subscribers' lines lead according to the invention to different switching units A_1, A_2, A_3 of the first group-selecting stage. A switching unit is designated by a larger circle and comprises all the selecting and connecting means (selectors and 10 relays) necessary for establishing the connections between the appertaining group of incoming lines l_1, l_2, l_3 and a number of groups I, II, III of outgoing junction lines m_1, m_2, m_3 . In a system according to the 15 present invention each group of incoming junction lines l_1, l_2, l_3 has associated with it separate selecting means adapted to be used in common by all the lines of said group. The switching units A_1, A_2, A_3 constitute 20 together the first group-selecting stage S_1 , in which the thousands groups G of subscribers' lines are selected.

As will be seen from the drawing, every subscriber's line has access to three (in practice ten or more) switching units A_1, A_2, A_3 and each group D_1, D_2, D_3 of three units is allocated to a group G of subscriber's lines. The lines l_1, l_2, l_3 common to a group g of subscribers' lines may also be connected to 30 units belonging to different groups D_1, D_2, D_3 . For instance, the lines l common to group G , may extend to the different units A_1 of the various groups D_1, D_2, D_3 , the lines l of group G_2 to the units A_2 and the lines l of 35 group G_3 to the units A_3 , or the lines l of all the small groups g_1 may extend to the units A_1 , the lines l of the groups g_2 to the units A_2 and the lines l of the groups g_3 to the units A_3 . By connecting the lines l of a 40 group g to units of different groups D we gain the advantage that all outgoing lines m of the first group-selecting stage are made available to every subscriber's line and thus a more even distribution of the connections 45 is obtained.

The various groups I, II, III of junction lines m outgoing from the first group-selecting stage S_1 extend to different groups G of subscriber's lines, viz.: the groups I to group 55 G_1 , groups II to group G_2 and groups III to group G_3 . The different lines m_1, m_2, m_3 of each group I, II or III lead according to the invention to different switching units B_1, B_2, B_3 of the second group-selecting stage S_2 , in 60 which the various hundreds groups g are selected. The various groups I, II, III of junction lines m outgoing from the second group-selecting stage extend in the usual manner to switching units C constituting 65 the line selecting stage S_3 through which the

connection with the wanted subscriber's line is completed.

The modification shown in Fig. 2 relates to systems in which the connections between the incoming and outgoing junction lines of a group-selecting stage are established over special intermediate lines. Fig. 2 shows only a group D_1 of switching units A_1, A_2, A_3 of the first group-selecting stage and the switching units B of the second group-selecting stage. A number of intermediate lines p are interposed between every group l_1, l_2 and l_3 of incoming lines and the outgoing lines m , every intermediate line having access to only one outgoing line of each group I, II and III and the various intermediate lines of the same unit having at their disposal different outgoing lines. All the intermediate lines of a switching unit are accessible to the appertaining incoming lines l . This arrangement is repeated in all group-selecting stages. As will be seen, every incoming line l can be connected with any of the outgoing lines m through an intermediate line p . The switching units comprise all apparatus necessary for establishing the connections between the incoming and outgoing lines l and m . The provision of intermediate lines, therefore, does not affect in any way the principle of the invention which refers to the arrangement of the incoming and outgoing lines.

Fig. 3 is a diagram of connections of a group-switching unit with intermediate lines as shown in Fig. 2. The connections are established by means of relays, one being provided for each connecting possibility. Thus, referring to Fig. 2, there is one relay for each small circle. The selecting means also consist of relays only. The incomplete switching unit shown in Fig. 3 comprises only two incoming lines l_1 and l_2 , two intermediate lines p_1 and p_2 , and two outgoing lines m_1 and m_2 of two different numerical groups. The outgoing lines m_1 and m_2 lead 100 to different switching units of the next selecting stage as shown in Fig. 2. The lines are connected together by means of connecting relays 1, 2, 3 and 4. Every incoming line consists of two talking wires 5 and 6, a holding or release wire 7 and a test wire 8. The intermediate lines and the outgoing lines m comprise corresponding wires 9, 10, 11, 12 and 13, 14, 15, 16 respectively. Allocated to every incoming line is a selector 105 connecting relay 17 by means of which the calling line can be connected with a selector 18 adapted to be used in common by all incoming lines for the selecting of the group wanted and consisting of switching relays 19, auxiliary relays 20 and controlling relays 21 and 22. For the purpose of selecting an idle line of the group wanted a searcher 23 is provided consisting of testing relays 24 and controlling relays 25, 26 and 27 and 110

130

ing relay 24 has been operated, which corresponds to the first intermediate line p_1 , not being accessible, a circuit is now established extending from earth through the 5 lower relay 74 corresponding to the second intermediate line p_2 , back contact 75 of the second relay 24, contact 76 of the first relay 24, contact 77 of relay 26, contact 78 of relay 27, contact 67, wire 41 and contact 42 10 to the battery. If upon the energization of the relay 25 none of the testing relays are energized owing to the fact that none of the intermediate lines of the outgoing junctions in the second group are engaged, the 15 relay 26 will operate by a circuit through contact 71 of relay 25, contact 124 of relay 27, resistance 125, coil of 26, contact 66 of relay 27 and contact 67 of relay 25. Relay 26 locks itself over its contact 70 and closes 20 a circuit for relay 27 through contact 71 of relay 25, contact 72 of relay 26 and contact 67 of relay 25. Relay 27 operates and locks itself over its contact 73 at the same time breaking the circuit for relay 26 at contact 124. A circuit is now established extending from earth through the upper relay 74 corresponding to the first intermediate line p_1 , in the same manner as was the lower relay 74 described above. Upon the energization of relay 74 a circuit is closed 30 extending from earth through contact 38 of relay 37, wire 39, contacts 57, 58, 59, 59, 60, wire 79, an operating winding of the lower relay 3, contact 80 of relay 74, contacts 75, 35 76, 77, 78, 67, wire 41 and contact 42 to the battery. The lower connecting relay 3 is thereby energized. Upon attracting its armature it connects earth to the testing wire 12 of the corresponding intermediate line p_2 , thereby closing a circuit from earth through test wire 12, contact 81 of the lower relay 74, contact 82 of the upper relay 17, wire 83, an operating winding of the upper connecting relay 2, wire 84, contact 85 of relay 74, contacts 75, 76, 77, 78, 67, wire 41 and contact 42 to the battery. The upper connecting relay 2 operates upon the closure of that circuit whereby a circuit is closed extending from earth at the holding wire 7 through a holding winding of the upper connecting relay 2, contact 86, wire 11 holding winding of the lower connecting relay 3, contact 87 and holding wire 15 to the battery at the next switching unit. A 55 connection is thereby established between the calling line l_1 and the outgoing line m_2 of the second group through contacts 88 of relay 2, intermediate line p_2 and contacts 89 of relay 3.

60 Upon the energization of the connecting relay 2 the circuit of the relay 17 was broken. The latter deenergizes and breaks the circuits of the relays 34 and 37 whereby the selector and the searcher are deprived 65 of current and restored to normal condition.

In the arrangement just described a switching unit is blocked as soon as its group selector is taken into engagement. Sometimes, however, it may be suitable to admit a subscriber into a switching unit even if the group-selector is engaged, in which case the latter subscriber has to wait until the selector is disengaged. The block relay 34, Fig. 3, is then to be operated only when there are two non-effectuated calls 70 within the unit. Fig. 4 shows such an arrangement. It may, of course, preferably be used only in systems having the impulse transmitters controlled from the exchange in such a manner that the impulses are not 75 sent out before a selector is connected to the line.

Fig. 4 shows two incoming lines l_1 and l_2 having two connecting relays 1 and 2 and two individual selector connecting relays 90 85 and 91. The relays 90 are adapted to connect a calling line to a common line 92, 93, 94 and the relays 91 are adapted to connect another calling line to a second common line 95, 96, 97. The wires 93, 94 and 96, 97 90 of said common lines can be connected separately by means of common selector connecting relays 98, 99 to the wires 43, 49 leading to the common selector. Two relays 100 and 101 are provided for controlling the 95 circuits of the relays 98 and 99 and the circuits of the block relay 34.

Supposing a subscriber connects his line to the incoming line l_1 a circuit is closed extending from earth at the holding wire 7 100 through said wire 7, contact 29 of relay 1, contact 30 of relay 2, contact 102 of relay 91, relay 90, contact 103 of relay 90 and contact 104 of relay 100 to the battery 31. Relay 90 operates and locks itself over its contact 105; it also closes a circuit through the holding wire 7, contact 106 of relay 90 and relay 100 to the battery. Relay 100 operates and causes a flow of current from earth through contact 107 of relay 101, contact 108 of relay 100 and relay 98 to the battery. Relay 98 operates and locks itself over its contact 109 and contact 110 of relay 100. At the same time the calling line is connected to the selector over contacts 111, 112 of relay 98 and contacts 32, 33 of relay 90. The switching unit is not yet blocked as the circuit of the block relay 34 is open at contact 113 of relay 101.

Supposing now another subscriber connects himself to the second incoming line l_2 a circuit is closed from earth at the holding wire 7 of that line through said wire, contacts 29 and 30, contact 114 of relay 90, relay 91, contact 103, contact 115 of relay 101 120 and contact 116 of relay 100 to the battery. Relay 91 operates, locks itself over contact 105 and cuts in relay 101 over contact 106. Relay 99, however, cannot yet be energized as its circuit is open at contact 117 of relay 130

adapted to be connected with the test wires 16 of any wanted group of outgoing lines by means of group relays 28.

When a calling subscriber connects his line with an incoming line, for instance, L_1 , a circuit is established over the holding wire 7, which is earthed in the next preceding switching unit, through contact 29 of relay 1, contact 30 of relay 2, and relay 17 to the negative pole of a battery 31 having its positive pole connected to earth. Relay 17 energizes and connects the wires 5 and 6 through contacts 32, 33 to the group selector 18. At the same time a block relay 34 is energized over contact 35 of relay 17, whereby the test wires 8 of all incoming lines of the switching unit in question are connected to earth through contacts 36 and 35. This switching unit is therefore marked as engaged or blocked as long as relay 17 is energized, that is as long as the group-selector is engaged. Those of the incoming lines which are engaged by a talking connection have their test wires permanently connected to earth at the next preceding switching unit. At the closing of contact 35 also a relay 37 is energized causing a flow of current from earth through contact 38, wire 39 and further parallelly through contacts 40 of auxiliary relay 20, switching relays 19, wire 41 and contact 42 of relay 37 to the battery, whereby all switching relays 19 of the selector are energized.

The group-selector is now operated by the selective impulses sent over the line branch 5, while the line branch 6 is continuously connected to earth. At first a circuit is closed extending from earth at the line branch 6 through line branch 6, contact 32, wire 43, contact 44 of relay 22, relay 21, wire 41 and contact 42 to the battery. Relay 21 operates and cuts itself into a locking circuit over its contact 45. At the same time relay 22 is supplied with current from earth through contact 38 of relay 37, wire 39, contact 46 of relay 21 and contact 47 of the first relay 19. It operates and locks itself over its contact 48. The first selective impulse is now sent from earth at the line branch 5 through line branch 5, contact 33, wire 49, contact 50 of relay 22, contact 51, of relay 21, contact 52 of the first switching relay 19, contact 53 of the first auxiliary relay 20, relay 20, wire 41 and contact 42 to the battery. Relay 20 operates and locks itself over its contact 54. The circuit of the first switching relay 19 is thereby broken at contact 40 but the relay is maintained energized by the selective impulse which now passes through contact 55 and relay 19. When the first selective impulse ceases the first switching relay 19 is deprived of current and releases its armature. The next impulse therefore passes through line branch 5, contact 33, wire 49, contacts

50 and 51, contact 56 of the first switching relay 19, contact 52 of the second switching relay 19, contact 53 of the second auxiliary relay 20, relay 20, wire 41 and contact 42 to the battery. The second auxiliary relay 20 operates with the same result as the first relay 20. When the second impulse ceases the second relay 19 is deenergized whereby a path is prepared for the third selective impulse over contact 56 of the second relay 19 and so on.

The group-selector having been set the line branch 6 is disconnected from earth and, consequently, the controlling relay 21 is deprived of current and releases its armature. A circuit is thereby closed from earth through contact 38 of relay 37, wire 39, contact 57 of relay 21, contact 58 of relay 22, back contacts 59 of all deenergized switching relays 19, contact 60 of the first energized relay 19, for instance, the third, the second group relay 28, wire 41 and contact 42 to the battery. The second group-relay operates and closes another path for the said current, viz. through contact 61 of said group relay and controlling relay 25 to the battery. At the same time the testing relays 24 of the searcher 23 are connected through contacts 62 of the second group-relay to the test wires 16 of the outgoing lines m_1, m_2 belonging to the second group. An outgoing line is marked as engaged if its test wire 16 is connected to earth through a contact 63 of a connecting relay 4 either in this switching unit or in another. The testing relays 24 are also connected with the test wires 12 of the intermediate lines p_1 and p_2 which are marked as engaged by their test wires being connected to earth through contacts 64 of the connecting relays 3 or 4. The searcher 23 therefore simultaneously tests both the outgoing lines of the group selected and the intermediate lines.

Upon the energization of the controlling relay 25 those of the testing relays are energized which correspond to engaged outgoing lines or intermediate lines. The circuits extend from earth either through a contact 63, wire 16 and contact 62 or through a contact 64 and wire 12, and further through the testing relay 24 in question, its contact 65, relay 26, contact 66 of relay 27, contact 67, wire 41 and contact 42 to the battery. The testing relays 24 in question operate and lock themselves over their contacts 68, a resistance 69 and contact 67. Relay 26 also operates, locks itself over its contact 70 and closes a circuit for relay 27 through contact 71 of relay 25, contact 72 of relay 26 and contact 67 of relay 25. Relay 27 operates and locks itself over its contact 73. At the same time relay 26 releases its armature, its circuit having been broken at the contacts 65 of the operated testing relays 24. Provide that only the first test-

100. Upon the energization of relay 101 the circuit of the block relay 34 is closed through contact 113 of relay 101 and contact 118 of relay 100, whereby the switching unit 5 is blocked for further calls.

As soon as the first calling subscriber has been connected through to the next selecting stage, the circuit of the corresponding relay 90 is broken at contact 29 or 30 whereby said relay 90, and, consequently also relays 100 and 98 are deenergized. The circuit of relay 99 is, therefore, now closed through contact 117 of relay 100 and contact 119 of relay 101. On energizing the relay 99 locks 15 itself over contacts 109 and 110 and connects the waiting subscriber's line l_2 to the selector. At the same time the switching unit is disengaged by the circuit of the block relay 34 being broken at contact 118.

20 In the arrangement above described it may happen that a subscriber is caused to wait although there are other accessible switching units in the same selecting stage having idle group-selectors. By adding the 25 circuits shown in dotted lines means are provided for blocking a switching unit even if there is only one call in the unit provided that another switching unit can be reached having an immediately available group-selector. For that purpose a relay 120 is provided which is common to a number of switching units, for instance, the units A_1 , A_2 , A_3 of a group D in Fig. 1. The relay 120 is adapted to operate only when the 30 group-selectors of all said units are engaged which may be effected in any known manner, for instance, by interposing series contacts, one for every selector in the circuit of said relay. The switching unit is then 35 normally blocked for only one call, that is as soon as the selector is engaged, the block relay 34 being energized over either of the contacts 121 and 122 and over contact 123 of relay 120. When all accessible selectors 40 are engaged, however, contact 123 is opened so that a second call may be admitted for waiting in any of the units except in those having already two calls which units are 45 blocked by their block relay 34 being energized over contacts 118 and 113.

What we claim is:

1. In a telephone system, the combination of a plurality of calling lines divided into groups, a plurality of groups of junction lines, the various junction lines of a group being accessible in common to the calling lines of the various groups, means for connecting a calling line to one of the junction lines, a numerical selecting device common to the junction lines, means for connecting the junction line connected to the calling line to the numerical selecting device, a plurality of outgoing lines, means for causing the selecting device to establish initial connection between a junction and an out-
2. In a telephone system, the combination of a plurality of calling lines divided into groups, a plurality of groups of outgoing lines, common numerical selecting means to which each line of each group of calling lines has access and adapted to be used in common by all the lines of such groups to select 70 and establish initial connection between an incoming and an outgoing line, means for maintaining the connection between the calling lines and the outgoing line when the selecting means is cut off, a plurality of 75 groups of second outgoing lines, second numerical selecting means associated with each group of first outgoing lines and adapted to be used in common by all the lines of said group to select and establish initial connection with an outgoing line, and means for maintaining a connection between a first outgoing line and a second outgoing line after the common selecting means is cut off.
3. In a telephone system, the combination 90 of a plurality of calling lines divided into groups, a plurality of groups of outgoing lines, the various lines of a group of outgoing lines being accessible to different groups of calling lines, common numerical 95 selecting means associated with each group of calling lines and adapted to be accessible to all the lines of said group and to select and establish initial connection with an outgoing line, means for maintaining the connection between a calling line and an outgoing line after the calling selecting means is cut off, a plurality of groups of second outgoing lines, second numerical selecting means associated with each group of first 100 outgoing lines and adapted to be used in common by all the lines of such group and to select and establish initial connection with an outgoing line and means for maintaining the connection between a first outgoing line 105 and a second outgoing line after the calling selecting means is cut off.
4. In a telephone exchange system, switching means of a group-selecting stage divided into a number of switching units, each comprising a plurality of incoming and outgoing lines, means for connecting said lines and common selecting means associated with the incoming lines, junction lines accessible in common to a group of subscribers' lines and 115 leading to different switching units of the group selecting stage, and means for blocking a switching unit when there is a certain maximum number of non-effectuated calls in that unit.
5. In a telephone exchange system, switching means of a group-selecting stage divided into a number of switching units, each comprising a plurality of incoming and outgoing lines, means for connecting said lines and 120

125

130

common selecting means associated with the incoming lines, means for blocking an engaged switching unit and means for connecting a calling line to an engaged switching unit after it has been ascertained that there are no selecting means immediately available in any of a number of switching units.

6. In a telephone exchange system, switching means of a group-selecting stage divided into a number of switching units, each comprising a plurality of incoming and outgoing lines, means for connecting said lines, and common selecting means associated with the incoming lines, means for blocking an engaged switching unit, means for raising the blocking of a switching unit when there are no selecting means available in any of a number of switching units and means for finally blocking a switching unit when there is a certain maximum number of non-effectuated calls in that unit.

7. In a telephone exchange system, switching means of a group-selecting stage divided into a number of switching units, each comprising a plurality of incoming and outgoing lines, means for connecting said lines, and common selecting means associated with the incoming lines, means for blocking an en-

gaged switching unit, means for connecting a calling line to an engaged switching unit after it has been ascertained that there are no selecting means immediately available in any of a number of switching units, and means for stopping the connecting operation until the selecting means are disengaged.

8. In a telephone exchange system, switching means of a group-selecting stage divided into a number of switching units, each comprising a plurality of incoming and outgoing lines, means for connecting said lines, and common selecting means associated with the incoming lines, means for blocking an engaged switching unit, means for connecting a calling line to an engaged switching unit after it has been ascertained that there are no selecting means immediately available in any of a number of switching units, means for stopping the connecting operation until the selecting means are disengaged and means for connecting two simultaneously calling lines separately and successively to the common selecting means.
